(57) **CLAIM**

We claim the ornamental design for a manifold sensor, substantially as shown and described.

DESCRIPTION

FIG. 1 is a perspective view of the manifold sensor in accordance with the present design.

FIG. 2 is a front elevational view of the manifold sensor of FIG. 1.

FIG. 3 is a rear elevational view of the manifold sensor of FIG. 1.

FIG. 4 is a left side elevational view of the manifold sensor of FIG. 1.

FIG. 5 is a right side elevational view of the manifold sensor of FIG. 1.

FIG. 6 is a top plan view of the manifold sensor of FIG. 1; and,

FIG. 7 is a bottom plan view of the manifold sensor of FIG. 1.

The broken lines shown on the drawing views are for the purpose of illustrating environmental structure and form no part of the claimed design.
